UNITED STATES PATENT OFFICE.

GEORGE MURGATROYD, OF PROVIDENCE, RHODE ISLAND.

DRYING ROLL OR CYLINDER.

SPECIFICATION forming part of Letters Patent No. 727,822, dated May 12, 1903.

Application filed November 27, 1901. Serial No. 83,878. (No model.)

To all whom it may concern:

Be it known that I, GEORGE MURGATROYD, a subject of the King of Great Britain, and a resident of the city and county of Providence and State of Rhode Island, have invented certain new and useful Improvements in Drying Rolls or Cylinders; and I do hereby declare the following specification, taken in connection with the accompanying drawings, forming a part of the same, to be a full, clear, and exact description thereof.

The invention relates to drying rolls or cylinders used in connection with the drying of fabrics, in the manufacture of cotton or paper, or in connection with other machinery where said rolls are constantly supplied and filled with live steam and it is necessary to remove the water of condensation substantially as fast as formed while the rolls are in operation.

One feature of the invention consists in providing an ejector that may be fastened longitudinally and parallel to the axis of the roll on the inner surface thereof.

Another feature of invention consists in a novel form of ejector adapted for use in rolls that may be run in either direction.

Another feature consists in a new method of fastening the spiral conductor forming a part of the ejector in long rolls.

The invention also consists of certain further features to be hereinafter described and claimed.

Any of said features of invention may be used in constructions where some or all of the other features are absent, or all of the features may be embodied in the same structure.

In describing my invention in detail reference will be made to the accompanying drawings, in which—

Figure 1 is a longitudinal section of a drying roll or cylinder embodying my improved water-ejector in its preferred form. Fig. 2 is a transverse sectional view on line $x-x$; Fig. 3 is a transverse sectional view of the double ejector for use in rolls running in either direction. Fig. 4 is a longitudinal sectional view of a roll provided with two ejectors. Fig. 5 is a longitudinal sectional view of a long roll, showing my improved spiral conductor forming a part of the ejector. Fig. 6 is a transverse sectional view on line $y-y$,

Fig. 5; and Fig. 7 shows a section of the spiral gutter detached.

Referring to the drawings, Fig. 1 represents a large size drying-roll having the cylindrical body portion 1 and the end portions 2 and 3, provided with hollow trunnions 4 and 5, respectively. On the inner surface of the roll is fastened my improved ejector, which I construct, preferably, in the form of a narrow chamber or pocket extending longitudinally of the roll and having an outlet-pipe 6 extending into the hollow trunnion 5. This chamber is preferably in the form of a right-angle triangle, the short side 7 extending substantially parallel to the end of the roll, the long side 8 extending longitudinally and fastened to the inner curved surface of the roll parallel to its axis, and the hypotenuse or inclined side 9 extending diagonally from the inner curved face of said roll to one of the hollow trunnions. The wall 10 of the ejector is preferably provided with a flange 11 for fastening said ejector to the inner curved surface of the roll, either by soldering or riveting or in any other desired manner. The opposite wall 12 is bent over and away from said wall 10 to form a curved flange 13, as shown in Fig. 2, extending substantially parallel to the inner curved surface of the roll, thereby forming an opening or inlet 14 to the pocket or chamber extending the entire length of the roll. As the steam in the roll condenses the water falls to the bottom 85 of the inner curved surface of the roll, and as said roll is revolved, bringing the wall 10 to the bottom thereof, the water enters the opening 14 and strikes the wall 10 of said roll, and as the roll continues to revolve the wall 10 lifts the water until said wall reaches a position above the horizontal, when the water will flow down said wall onto the inclined side 9 and down said side and out through the opening or outlet 6.

As shown in Fig. 2, the curved flange 13 acts both as a guide to direct the water into the opening in ejector and as a guard to prevent the water from flowing back and away from the inlet until the wall 10 reaches a position above the horizontal, when the water will flow down said wall into the outlet-pipe 6. The wall 12 is preferably constructed to converge toward the wall 10 as it approaches the

wall of the cylinder, thereby contracting the inlet, as shown in Fig. 2, and thus decreasing the liability of the water which may remain in the ejector during the last quarter-turn of 5 the revolution of the roll escaping through the inlet.

Fig. 3 shows my improved ejector in its double form, which is adapted for use in rolls to be run in either direction. In this construction the ejector has a center wall or partition 10' and two side walls 12 12'. The outlet-pipe 6 may also be provided with a center wall, if desired; but this is not essential. With this construction a pocket or 15 ejector is formed on each side of the center wall 10, provided with openings 14 14' to each of said pockets, respectively. Thus as the roll is revolved in one direction the water will strike the center wall 10' on one side and 20 be raised by it until it will enter the opening to the pocket on that side of said center wall. If it should be desired to reverse the roll and run it in the other direction, the water will be raised so as to enter the pocket on the other 25 side of said center wall.

Fig. 4 shows two of my improved ejectors in one roll. In rolls of a large diameter, which necessarily contain a larger amount of steam and which revolve slower than the ordinary-sized rolls, the water will collect quite 30 rapidly, and in such rolls the ejectors now in use are found inadequate to accommodate all the water that may collect in one revolution. With my improved form of ejector I can place 35 two or more ejectors in one roll by simply dividing the outlet-pipe into different sections corresponding to the number of ejectors. As shown in Fig. 4, the partition 6' divides the outlet 6 into two parts or sections, 40 thereby forming a separate outlet-pipe for each ejector. This prevents the water flowing from one ejector into the other, as might be the case were there a single outlet-pipe for both ejectors.

Fig. 5 shows my improved spiral conductor forming a part of the ejector in use in a long roll, and Fig. 6 shows my improved method of fastening said conductor. With the spiral conductors now in use it is impossible to fasten 45 them securely to the curved inner surface of the roll, and they are very liable to be forced or sprung away from their fastenings when the roll is subjected to a continual hard pressure on the outside surface. To overcome 50 this objection, I construct my improved conductor in sections adapted to be fastened longitudinally to the roll, and not spirally, as heretofore. To accomplish this, I construct

each section preferably of a flat piece of tin having one edge beveled. This beveled edge 60 15 is bent up at right angles to the body portion 16, forming a beveled side 17. I preferably bend the upper edge of said side 17 back again over the body portion 16 and parallel to it to form a top or cover 18 to said 65 conductor. The body portion 16 is then preferably rolled to conform with the inner curved surface of the roll, and said section is fastened to the roll by solder or rivets along the straight edge 19. This makes a firm and rigid fastening for said spiral conductor and also obviates the necessity for the strengthening rings or spiders now in use. The sections forming the spiral conductor may be joined together in any well-known manner; but it 70 is preferred to overlap said sections at their joints in order to strengthen the same and prevent any leakage at this point. If desired, the conductor may be constructed of one continuous piece of metal provided with triangular flanges instead of being formed in triangular sections.

What I claim as my invention, and desire to secure by Letters Patent, is—

1. An ejector for use in drying-rolls constructed substantially in the form of a triangular pocket extending longitudinally of said roll and having one of its sides provided with a flange for fastening said pocket to the roll and its opposite side cut away and provided 90 with an outwardly-extending curved flange for guiding the water into said pocket, an outlet, and an inclined side for conducting the water of condensation into said outlet, substantially as described. 95

2. The combination, with a drying-roll, of a water-ejector in the form of a triangular pocket extending longitudinally of said roll and provided with a flange for fastening said pocket to the inner curved surface of the roll 100 and a spiral conductor provided with a series of flanges for fastening said conductor to the roll, the lines of fastening of said pocket and conductor being parallel to the axis of said roll, substantially as described. 105

3. The combination, with a drying-roll, of a water-ejector in the form of a triangular pocket and a spiral conductor fastened to the inner curved surface of the roll, the lines of fastening being parallel to the axis of the roll, substantially as described. 110
